UNITED STATES PATENT OFFICE

146,973

DESIGN FOR A LIGHTER

Richard F. Landwehr, Laurelton, N. Y., assignor to American Safety Razor Corporation, Brooklyn, N. Y., a corporation of Virginia

Application December 29, 1945, Serial No. 125,187

Term of patent 14 years

(Cl. D48—27)

To all whom it may concern:

Be it known that I, Richard F. Landwehr, a citizen of the United States, residing in Laurelton, Long Island, county of Queens and State of New York, have invented a new, original, and ornamental Design for a Lighter, of which the following is a specification, reference being had to the accompanying drawings, forming part thereof.

Fig. 1 is a front elevational view of a lighter showing my new design;

Fig. 2 is an end elevational view thereof;

Fig. 3 is a top plan view thereof; and

Fig. 4 is a perspective view thereof.

I claim:

The ornamental design for a lighter, as shown.
RICHARD F. LANDWEHR.
